UNITED STATES PATENT OFFICE

REINHARD HILDEBRAND, OF WEBSTER GROVES, MISSOURI

LEAD CONTROL FOR DIESEL ENGINES

Application filed November 3, 1930. Serial No. 492,934.

This invention relates to devices of the kind commonly referred to as "lead controls" that are used on Diesel engines to change the relationship between a driving member on a driving shaft of the engine, and a driven member on the cam shaft of the fuel injection pump in order to vary the period in the cycle of operations of the engine at which fuel is sprayed or injected into the cylinders, 10 the term "lead angle" being generally understood to mean the angle of the crank shaft before it reaches its upper dead center at the moment the fuel spray begins.

The main object of my invention is to 15 provide a lead control for Diesel engines, which is of such design that the lead of the engine can be changed while the engine is in operation, thereby overcoming an inherent objectionable characteristic of lead controls 20 of conventional design which necessitates stopping the engine each time the lead of the engine is changed.

Another object is to provide an inexpensive lead control of the type mentioned, that 25 is of rugged construction and of such design that the operator in charge of the engine can easily adjust the lead to suit the load, and moreover, is supplied with a visual gauge or indicator which shows whether the lead is 30 near its maximum or minimum. Other objects and desirable features of my invention will be hereinafter pointed out.

Figure 1 of the drawings is a front elevational view of a lead control for Diesel engines constructed in accordance with my invention.

Figure 2 is a detail sectional view, taken on the line 2-2 of Figure 1.

Figure 3 is a vertical transverse sectional view of the housing that encases the chain and sprockets used to transmit movement from the crank shaft of the engine to the cam shaft of the fuel injection pump; and

Figure 4 is a detail sectional view of the 45 hand wheel used to actuate the stops or abutments that are associated with the idler carriers.

In the accompanying drawings which illustrate the preferred form of my invention, 50 A designates a driving member, such for

example, as a sprocket, attached to the crank shaft of the engine, B designates a driven member, such as a sprocket, attached to the cam shaft of the fuel injection pump, and C designates a flexible endless member, such as a chain that co-operates with said sprockets to drive the fuel pump from the crank shaft of the engine. The pump driving chain C is held in operative relationship with the teeth of the sprockets with which it co-operates by means of two idler sprockets D and D' arranged at opposite sides of said chain, as shown in Figure 3, so as to take up the slack in the chain between the driving sprocket A and the driven sprocket B. The idlers D and D' are mounted so that they can be shifted bodily either to the right or to the left, looking at Figure 3, so as to cause the sprocket B to rotate slightly relatively to the driving sprocket A, thereby changing the relationship between the driven member on the pump and the driving member on the crank shaft of the engine, and thus varying the period in the cycle of operations of the engine at which fuel is sprayed into the cylinders. Diesel engines of conventional design are equipped with parts of the general character and arrangement above described, but in conventional designs the take-up idlers D and D' are so constructed and arranged that it is necessary to stop the engine preparatory to moving or shifting said idlers to effect a change in the lead of the engine. Usually, the take-up idlers are mounted on carriers that are capable of being adjusted when the engine is stopped, but said carriers are normally held stationary or at rest.

As previously stated, the main object of my invention is to overcome the necessity of stopping a Diesel engine whenever the lead of the engine is to be changed, and provide a simple means by which the operator in charge of the engine may quickly change the lead to suit the load while the engine continues in operation. To this end I have devised a lead control, which, briefly described, comprises a spring, weight, or other yieldable force for causing the take-up idler at the slack side of the flexible pump driving element C to exert pressure on said element in a direction

tending to hold said element taut, and a shiftable stop or abutment capable of being adjusted manually while the engine is in operation for resisting bodily movement of the 5 take-up idler at the tight side of the flexible pump driving element in a direction opposite to the lateral force or pressure which said pump driving element exerts on said idler. In the case of an engine whose crank shaft is 10 intended to rotate in only one direction, it will suffice if an adjustable stop or abutment is provided to oppose the outward movement of the idler that acts on the tight side of the flexible pump driving element, and a 15 spring or equivalent means is used to yieldingly hold the other take-up idler in engagement with the slack side of the pump driving element, but in an engine whose crank shaft is adapted to rotate either in clockwise or in anti-clockwise direction, it is necessary to provide an adjustable stop or abutment for each of the take-up idlers and also 20 combine a spring or equivalent means with each of the take-up idlers so as to effect the 25 necessary reversal in the bodily movement of the take-up idlers when the direction of rotation of the crank shaft of the engine is changed.

I have herein illustrated my invention embodied in a lead control for a reversible Diesel engine, but I wish it to be understood that the invention is applicable to an engine whose crank shaft is intended to rotate in only one direction and also that various changes may 30 be made in the design, construction and arrangement of the co-acting parts of the apparatus without departing from the spirit of my invention. As shown in Figure 3, the idlers D and D' are mounted on shiftable carriers 1 and 1^a, preferably rockable carriers, arranged at opposite sides of the pump driving chain D and rigidly attached to horizontally disposed rock shafts 2 and 2^a that project forwardly through the front wall of the 35 housing E that encases the mechanism used to transmit movement from the drive shaft of the engine to the cam shaft of the fuel injection pump. The arms 3 and 3^a that are rigidly attached to the front ends of the rock shafts 2 and 2^a, respectively, co-operate with a control mechanism or adjusting mechanism which comprises springs 4 and 4^a for moving the idler carriers 1 and 1^a inwardly towards each other, stops or abutments 5 and 5^a for controlling the position of the take-up idlers that act on the tight side of the chain C, and a manually-operated adjusting shaft 6 for shifting or changing the position of the stops 5 and 5^a. Various means may be 40 used for moving or shifting the adjusting shaft 6, the means herein illustrated for this purpose consisting of a hand wheel 7 rotatably mounted on a stationary bearing 8 and provided with a nut or internally-threaded bushing 9 that receives an externally screw-

threaded spindle 10 on a cross head 11 which is reciprocatingly mounted in the bearing 8. Said cross head is held against rotary movement by laterally-projecting pins 12 thereon that enter elongated slots 13 in the bearing 8, and the adjusting rod 6, previously referred to, is connected by links 14 or in any other suitable manner to the cross head 11, so as to cause the adjusting rod 6 to move endwise when the hand wheel 7 is rotated. 75 Pins or bearings 15, which are rockably mounted in the upper end portions of the arms 3 and 3^a, are provided with holes through which the adjusting rod 6 passes freely, and the stops or abutment members 5 and 5^a, previously referred to, are mounted on the rod 6 in such a position that the stop 5 is arranged on the outside of the arm 3 and the stop 5^a is arranged on the outside of the arm 3^a. The springs 4 and 4^a, previously referred to, are contractile springs and are attached at their outer ends to the arms 3 and 3^a, respectively, and attached at their inner ends to a bearing 16, rigidly mounted on the adjusting rod 6. In order that the operator in charge of the engine may easily ascertain whether the lead is near its maximum or minimum, the cross head 11, previously referred to, is provided with a pointer, designated by the reference character 17 in Figure 1, that co-acts with a dial 18 carried by the bearing 8 in which the cross head reciprocates, and provided at its opposite ends with the words "Minimum" and "Maximum". 90

When the crank shaft of the engine is rotating in clockwise direction the tight side of the chain C, i. e., the right hand side, will tend to move the right hand idler D outwardly, or to the right, looking at Figure 3, thereby causing the arm 3 that is attached to the carrier 1 of said idler to press tightly against the stop or abutment 5 on the adjusting rod 6. At such times the spring 4^a that is associated with the left hand idler D', which acts on the slack side of the chain C, exerts an inward pull on the arm 3^a, with the result that the left hand idler D' will exert pressure on the chain C in a direction to take up the slack in said chain and hold it in operative relationship with the driving sprocket A and the driven sprocket D. By moving the stop 5 to the right or to the left, the right hand idler D will be shifted bodily, thereby effecting a change in the relationship between the driving sprocket and the driven sprocket, and thus causing the lead of the engine to be changed. So long as the engine continues to rotate in clockwise direction the stop 5^a associated with the idler D' that acts on the slack side of the chain C will remain inactive, and said left hand idler will be held yieldingly in engagement with the chain by the pressure which the spring 4^a exerts on the carrier of said idler. When the engine is reversed or 100

caused to rotate in anti-clockwise direction, the left hand side of the chain C becomes tight and the right hand side slack, with the result that the chain exerts pressure on the 5 idler D' in a direction tending to move it outwardly, or to the left, looking at Figure 3, whereupon the stop or abutment 5^a will come into action to restrict or resist the outward movement of the idler D'. The stop 5 is now 10 in an inactive condition or out of engagement with the bearing in the upper end portion of the arm 3 through which the adjusting rod 6 passes, and so long as the engine continues to rotate in anti-clockwise direction, the stop 5 will remain inactive and the 15 spring 4 that is associated with the right hand idler will cause said idler to act on the slack side of the chain C and take up the slack in the chain. No matter in what direction the 20 crank shaft of the engine turns, it will be seen that the idler on the slack side of the chain C will be held against the chain by the pressure of the spring that is associated with the carrier on which said idler is mounted. 25 Hence, the force exerted by this idler is yielding and self-adjusting. Conditions are different on the tight side of the chain, as this idler is held in position not only by its spring, but also rigidly by the co-action of the carrier 30 of said idler with the stop on the adjusting rod 6. Assuming that the crank shaft of the engine is rotating in clockwise direction, the right hand side of the chain C tends to straighten out, but is prevented from 35 straightening out fully by the spring 4 and the stop 5 that limits the outward movement of the carrier 3. By turning the hand wheel 7 in one direction or the other the lead angle can be accurately increased or decreased, with 40 the result that the operator in charge of the engine can accurately adjust the lead to suit the load. Regardless of whether the lead is increased or decreased, the take-up idler that acts on the slack side of the chain C will always hold 45 said chain steady, due to the fact that said idler is under the influence of a spring or similar means which holds it yieldingly in engagement with the chain.

Owing to the fact that the above described 50 adjustments or changes in the position of the carriers for the take-up idlers may be made while the engine is in operation, the injection of the fuel into the cylinders of the engine can be accurately controlled to secure efficient 55 operation of the engine. Such a lead control is inexpensive to manufacture; it is of sufficiently rugged design to insure its standing up successfully while in use, and in addition to being easy to adjust, enables the operator 60 in charge of the engine to easily determine whether the lead is near its maximum or minimum.

In some instances the idler on the slack side 65 of the chain has a tendency to flutter while the engine is in operation, due to the fact

that said idler is not held rigidly in place, and the force transmitted by the chain is continuously varied. If desired, my improved lead control can be provided with a means for overcoming this, which means may consist of a nut 19 mounted on the adjusting shaft 6, as shown in Figure 1, and adapted to be screwed against the arm 3^a, after the lead has been adjusted to best suit the load and speed of the engine.

Having thus described my invention, what I claim as new and desire to secure by Letters Patent is:

1. In a lead control for Diesel engines, the combination of a flexible driving element for transmitting movement from a driving shaft of the engine to the fuel injection pump, shiftable idlers that act on opposite sides of said flexible element, means for holding the idler at the slack side of the element in yielding engagement with the same, and a means capable of being adjusted while the engine is in operation for bodily shifting the idler at the tight side of said flexible element to change the lead of the engine.

2. In a Diesel engine, the combination of a driving member operated by a driving shaft of the engine, a driven member associated with a fuel injection pump, an endless flexible element for transmitting movement from said driving member to said driven member, idlers at opposite sides of said flexible element for taking up the slack in same, an adjustable stop for controlling the position of the idler that acts on the tight side of said flexible element, and means for holding the other idler in yielding engagement with the slack side of said flexible element.

3. In a Diesel engine, the combination of a driving sprocket operated by a driving shaft of the engine, a driven sprocket associated with the fuel injection pump, an endless sprocket chain that travels over said sprockets, take-up idlers at opposite sides of said chain, bodily shifting carriers for said idlers, means associated with said carriers for causing said idlers to exert pressure on said chain in a direction tending to take up the slack in same, and shiftable stops under control of the operator in charge of the engine capable of being moved while the engine continues in operation for varying the position of the carrier of the idler that acts on the tight side of the chain.

4. In a Diesel engine, the combination of a driving sprocket connected to a driving shaft of the engine, a driven sprocket attached to the cam shaft of the fuel injection pump, an endless chain that travels over said sprockets, take-up idlers arranged to act on the opposite sides of said chain, means which constantly exerts pressure on said idlers in a direction tending to move them towards each other, and an adjustable means under control of the operator in charge of the en-

gine for limiting the outward movement of either of said idlers, produced by the outward force or thrust which the tight side of the chain exerts on the idler that acts on same.

5. In a Diesel engine, the combination of a driving sprocket connected to a driving shaft of the engine, a driven sprocket connected to the cam shaft of the pump, an endless chain that travels over said sprockets, take-up idlers arranged at the opposite sides of said chain, rockable carriers for said idlers, springs associated with said carriers and arranged so as to exert pressure on the idlers in a direction tending to move them inwardly towards each other, and a manually-operated adjusting rod provided with stops or abutments arranged so as to restrict or limit the outward movement of the take-up idler that acts on the tight side of the chain.
- 10 6. In a Diesel engine, the combination of a driving sprocket attached to a driving shaft of the engine, a driven sprocket combined with the fuel injection pump, an endless chain that travels over said sprockets, take-up idlers arranged at opposite sides of said chain, rockable carriers for said idlers, an arm combined with each of said carriers, a manually-operable adjusting shaft that passes freely through openings in the free 15 end portions of said arms, a bearing on said rod, contractile springs connected to said bearing and to the upper end portions of said arms for causing said idlers to exert pressure on said chain in a direction tending to take up the slack in same, and stops on 20 said rod arranged at the outer side of said arms for limiting the outward movement of the take-up idler which acts on the tight side of the chain.
